UNITED STATES PATENT OFFICE.

WILLIAM H. PARKER, OF LEIPSIC, OHIO, ASSIGNOR TO THE TEMCO ELECTRIC MOTOR COMPANY, OF LEIPSIC, OHIO, A CORPORATION OF OHIO.

LOCK-SWITCH.

1,276,401.

Specification of Letters Patent. Patented Aug. 20, 1918.

Application filed July 31, 1916. Serial No. 112,311.

To all whom it may concern:

Be it known that I, WILLIAM H. PARKER, a citizen of the United States, and a resident of Leipsic, in the county of Putnam 5 and State of Ohio, have invented a certain new and useful Lock-Switch; and I do hereby declare the following to be a full, clear, and exact description of the invention, such as will enable others skilled in 10 the art to which it appertains to make and use the same, reference being had to the accompanying drawings, and to the characters of reference marked thereon, which form a part of this specification.

15 My invention relates to lock switches, and it has for its object to provide a means for inclosing a switch and locking the inclosing means and the means for operating the switch. It also has for its object to provide suitable stops for the switch which 20 form a part of the locking means. It also has for its object to provide an efficient durable lock switch which may be readily assembled and may be made at a low cost.

25 Structures containing the invention may partake of different forms. I have shown in the drawings a preferred form of the structure.

Figure 1 of the drawings is a front view 30 of the lock switch containing my invention. Fig. 2 is a view of the switch, the locking parts being removed. Fig. 3 is a rear view of the cover showing the locking parts secured thereto. Fig. 4 is a sectional view 35 taken on the line 4—4 indicated in Fig. 1. Fig. 5 is a perspective view of the shell which contains the locking barrel. Fig. 6 illustrates a lock plate.

1, Fig. 1, is a switch block which is 40 formed of an insulating material and is recessed to form an inclosing casing. A circular block 2 is located within the switch block and rests upon the bottom of the switch block. The block 2 is provided with 45 an arcuate contact 3 and is moved so as to complete a circuit through the contact 3 from the contact 4 to the contact 5 or from the contact 4 to the contact 6, which are secured to the bottom of the insulating block 50 1 by suitable nuts and screws. The block 2 is rotated by the arm 7. An external circuit, such as for engine ignition, is connected to the contacts 4, 5 and 6 in any suitable manner.

55 The block 2 is closed by the cover 10 and

through the center of the cover 10 is inserted a shell 11 having a locking barrel 12 of any of the forms well known in the art. The arm 7 is keyed to the shell 11 for purposes of rotating the shell 11 relative to the switch block 1. A ring 13 is secured to the shell 11 on the inside of the cover 10 to prevent axial movements of the shell relative to the cover and yet permit rotative movements of the shell. If desired a locking ring 14 may be threaded onto the shell 11 to secure the ring 13 in its position. A plate 15 is secured to the inner end of the shell 11 by means of screws 16. The plate is provided with lugs 17, which may be 70 struck up from the plate 15, while the shell 11 is provided with lugs 18, which fit into the spaces formed by the striking up of the lugs 17. The lugs 17 are located at a distance from each other substantially equal 75 to their width, that is, their outside transverse measurements form a square. The circular block 2 is provided with a hub 20 having an opening or hole 21 into which the lugs 17 may readily slip and thus connect the block 2 to the shell 11. The opening in the construction shown is made 80 square to key the hub 20 to the locking means. When the cover 10 is placed upon the block 1 the lugs 17 will enter the hole 85 21 and thus the block 2 will be keyed to the shell 11 and will be rotated when the shell 11 is rotated by the arm 7.

The barrel 12 is provided with a pin 25, which is located at one end of the barrel and 90 eccentrically thereto. A lock plate 26 is slidably movable between the end of the shell 11, the plate 15 and the lugs 18. The lock plate 26 is provided with a slot 27 into which the pin 25 extends so that as the barrel 12 is 95 rotated by the operation of a key the pin 25 will shift the plate 26 relative to the end of the shell 11. The lock plate 26 is provided with projections 28 and 29. A plate 30 is secured to the cover 10. The plate 30 is also 100 provided with projections 31 and 32 and 33, which are located in the path of movement of one or the other extensions 28 or 29 formed on the lock plate 26. The projections 31 on the plate 30 are disposed apart 105 about the width of the projection 28, while the projections 32 and 33 are disposed at a distance which angularly measures the same as that in which the switch member 3 is rotated to make contact between the contacts 110.

4 and 5 or 4 and 6. When the lock plate 26 is moved in one direction by the operation of the pin 25 the projection 28 will be inserted between the projections 31 and the arm will be locked in position and so that the contact 3 will make contact only with the contact 4. Rotation will be prevented in either direction by the projection 28 engaging with either of the projections 31. When, however, the lock plate 26 is moved so as to draw the projection 28 from between the projections 31, the projection 29 will be extended outward so as to strike either the projection 32 or 33 when the switch arm 7 is swung to the right or to the left, when at the same time a circuit will be completed between the contacts 4 and 5 or 4 and 6. The projection 29, when the contact 3 is well placed so as to make good connection will strike against one or the other of the projections 32 or 33 and thus prevent further rotation of the arm. The projections 32 and 33 thus form limiting stops to prevent rotation of the switch member 3 beyond that of making good circuit connections between its associated contacts. The projection 28 is then placed in such a position that the plate 26 cannot be moved by the barrel 12 as it will strike one or the other of the projections 31. Means is thus provided for preventing the locking of the switch unless the circuits are broken by the switch. The plate 30 is provided with a lip 35, which extends into the switch block 1 and engages a lip 36. When the cover is placed on the switch block the projections 17 are inserted in the opening 21 and the cover is slightly turned so as to cause engagement between the lips 35 and 36. The screws 37 and 38 are then threaded in the block.

The arm 7 is formed of a flat strip of metal and is made relatively broad. The projections 31 and 28 are so located on the shell 11 and the plate 30 as to lock the arm 7, which is keyed to the shell 11, in a certain position. A screw 40 is located in the cover and the block so that its head is located intermediate the arm 7 and the cover of the block and the screw cannot be removed when the arm is over the screw. The screw 40 thus forms a locking means to prevent the cover from being removed from the switch block when the arm 7 is locked by the barrel 12. The screw 40 may thus be inserted only when the barrel is unlocked so that the arm 7 may be turned to one side, and the screw 40 may not be removed when the barrel 12 is in locking position.

The structure selected and described may be modified in the arrangement and manufacture of its parts and the substitution of elements having equivalent functions, and such modifications may still contain the invention.

What I claim is:

1. In a lock, the combination of a shell having a lock, an arm connected to the shell for rotating the shell, a rotative member connected to the arm through the shell, a fixed member having projections, a movable member having projections for engaging the projections of the first named member to lock the rotative member when in one position and to limit the movements of the rotative member when in another position. 65
2. In a lock, the combination of a casing, a rotative member located in the casing, a shell, a locking means located in the shell, an arm connected to the shell for rotating the rotative member, a cover for inclosing the rotative member and supporting the shell for rotative movements, a plate secured to the cover and having projections, a second plate located on the end of the shell and movable transversely relative to the end of the shell and the first named plate and having projections for engaging the projections of the first named plate to lock the shell and the rotative member from rotation and to limit the movement of the rotative member and the arm in their rotative movements. 75
3. In a lock, the combination of a shell having a lock, an arm connected to the shell for rotating the shell, a rotative member connected to the arm through the shell, a fixed member having projections, a movable member having projections for engaging the projections of the first named member to lock the rotative member when in one position and to limit the movements of the rotative member when in another position, a casing for containing the rotative member, a cover for closing the casing, and a locking means for locking the cover to the casing. 80

In testimony whereof, I have hereunto signed my name to this specification.

WILLIAM H. PARKER.
